UNITED STATES PATENT OFFICE.

KARL H. H. LEINEWEBER, OF SOUTH CHICAGO, ILLINOIS.

CAR-BRAKE.

SPECIFICATION forming part of Letters Patent No. 317,553, dated May 12, 1885.

Application filed November 24, 1884. (No model.)

To all whom it may concern:

Be it known that I, KARL H. H. LEINEWEBER, a subject of the Emperor of Germany, residing at South Chicago, in the county of Cook and State of Illinois, have invented certain new and useful Improvements in Car-Brakes, of which the following is a specification, reference being had therein to the accompanying drawings.

10 My invention relates to an improved car-brake. The object it has in view is to improve the general construction of such brakes; and to that end it consists of the novel devices and combination of devices, as will be described.

15 In the drawings, Figure 1 is a side elevation of a truck; Fig. 2, a view on an enlarged scale of parts thereof; Fig. 3, a section on line 1 1 of Fig. 2; Fig. 4, a detail of the shoe-operating mechanism; Fig. 5, a section on line 2 2 of Fig. 2; Figs. 6 and 7, details of parts of the brake mechanism; Fig. 8, a view of the brake-shoe; Fig. 9, a view of the brake-block; Figs. 20 10 and 11, detail sectional views of the parts shown in Figs. 6 and 7, and Fig. 12 a section showing brake-block.

Like letters refer to like parts in each view.

25 A represents the car-wheels, B the truck-frame, and C suitable hangers secured to such frame for the support of the operative parts of the brake mechanism.

30 Suspended from hangers C are suitable beams, D, preferably of the shape shown in Fig. 1, and adapted to support hangers E. As shown in Fig. 3, each hanger E consists of a frame formed of suitable side pieces and cross-pieces, a a', the cross-piece a serving as the bottom of the frame, and cross-piece a' as a bearing for a vertical shaft, F, to be referred 35 to. One side piece of each hanger is bent to partly surround beam D and be supported thereby, while the hangers upon the opposite sides of the car are connected in pairs by rods b.

40 45 The shaft F, above referred to, is passed through suitable openings formed in cross-pieces a a', and is held in position by a nut, c. Upon this shaft midway of the two cross-pieces there is formed a cam, d, the shape of 50 which is shown in Fig. 5, while keyed to such shaft at a point below the hanger E is a screw-cam, G. The shaft F extends below this cam

55 G, and is inserted into a socket, e, formed upon a block, H, to be mentioned. Upon its lower end shaft F is provided with a head, f, against which one end of a coil-spring, g, im- 55 pinges, the other end of said spring contacting with the top of socket e, whereby the block H is raised when pressure is not applied.

60 J represents the brake-block, and consists of a piece provided with grooves h h and k k, the former adapted to receive projections l l, formed upon the inner side faces of hangers E, thereby providing a guide for such blocks in their lateral adjustment, and the latter, k k, 65 adapted to receive projecting pieces m m, formed upon the rear face of brake-shoes K. Formed upon the rear face of each brake-shoe, and at a point between pieces m, is a screw, 70 n, adapted to enter an opening, o, formed in the block J. Blocks J are situated in hangers E and with respect to shaft F and its cam d that upon a partial revolution of such shaft the cam d will contact with two of such blocks and force them outwardly in opposite directions. 75 As these blocks are thus forced outwardly, the shoes secured thereto are brought into contact with the car-wheels, and a brake thus supplied.

80 It will be understood that the revolution of shaft F may be accomplished through the medium of a lever L, and any suitable mechanism. While for all ordinary purposes the brake above described will be found sufficient, under certain circumstances, when a sudden stop may be desired, it will be found beneficial to apply the additional brake, which I have supplied for use in connection with the parts described.

85 In Fig. 6 I have represented a block, H, upon which the socket e is formed, this block being suspended on shaft F by the arrangement described, and being held up by spring g. Upon the upper face of block H a groove, p, is formed, into which the cam G enters to 90 depress said block. Upon the first partial revolution of shaft F, the brake-blocks J only are operated; but upon the further revolution of said shaft the cam G serves to press block H downwardly. Upon each end of block H 95 there is formed a notch or groove, q, into which a flange, r, formed upon the brake-shoe, is adapted to enter, thereby insuring a steady movement to block H. As shown in Figs. 10, 100

11, there are suitable recesses formed in the under face of block H, in which pieces M are pivoted, said pieces being of the shape shown and adapted to partially surround the rail 5 when the block is depressed, as described. By this arrangement it will be seen that a firm grasp upon the rail is obtained, and a thorough and effective brake secured.

O represents suitable springs forming connection between the hangers and truck-frame.

What I claim is—

1. In a car-brake, the combination, with a brake-shoe provided with a screw-threaded projection or pin, of a brake-block provided 15 with a screw-threaded socket for the reception of such pin, and a cam-shaft and lever for operating such blocks and shoes, as set forth.

2. In a car-brake, the combination, with a 20 brake-shoe provided with suitable projections, of a brake-block formed with grooves for the reception of such projections, and a cam-shaft and lever for operating the blocks and shoes, as set forth.

3. In a car-brake, the combination, with a 25 brake-shoe provided with a screw-threaded adjusting-pin and suitable strengthening-pins, of a brake-block provided with a screw-threaded socket, and suitable grooves for the reception of such parts, and a cam-shaft and 30 lever for operating the blocks and shoes, as set forth.

4. In a car-brake, the combination, with 35 suitable shoes, blocks, and a vertical shaft, of a screw-cam secured to said shaft, a block suspended on the shaft and adapted to be de-

pressed by the screw-cam, and suitable pieces pivoted to said block and adapted to clasp the rail, as set forth.

5. The combination, with shaft F, provided with cam d, of blocks J, provided with screw-threaded socket o, shoes K, provided with screw-threaded pin n, and lever L, for operating the parts. 40

6. The combination, with shaft F, provided with cam d and lever L, for operating said 45 shaft, of block J, provided with grooves h h, and shoe K, provided with pins m m, as set forth.

7. The combination, with shaft F, provided with cam d and lever L, for operating said 50 shaft, of blocks J, provided with socket o and grooves h, and shoe K, provided with pins m n, as set forth.

8. The combination, with shaft F, provided with screw-cam G and lever L, for operating 55 it, of block H, provided with socket e and groove p, and pieces M, pivoted to said block, as set forth.

9. The combination, with shoes K and lever L, for operating them, of block H, moving on 60 guides formed on said shoes, suitable mechanism for operating such block, and pivoted pieces M, as set forth.

In testimony whereof I affix my signature in presence of two witnesses.

KARL H. H. LEINEWEBER.
